UNITED STATES PATENT OFFICE

121,629

DESIGN FOR A BILLBOARD

Raleigh W. Barbour, Helena, Mont., assignor to Outdoor Bulletins, Helena, Mont.

Application April 1, 1940, Serial No. 91,393

Term of patent 7 years

To all whom it may concern:

Be it known that I, Raleigh W. Barbour, a citizen of the United States and resident of Helena, in the county of Lewis and Clark and State of Montana, have invented a new, original, and ornamental Design for a Billboard, of which the following is a specification, reference being had to the accompanying drawing, forming part thereof.

In the drawing:

I claim:

The ornamental design for a billboard, as shown.

RALEIGH W. BARBOUR.
